PREPARATION OF NAPHTHENIC ALCOHOLS

Charles A. Cohen, Roselle Park, and Louis A. Mikeska, Westfield, N. J., assignors to Esso Research and Engineering Company, a corporation of Delaware

No Drawing. Application December 22, 1951,
Serial No. 263,007

1 Claim. (Cl. 260—617)

This invention relates to an improved process for preparing water-soluble sulfates especially suited for use as detergents. More particularly, this invention relates to an improved process for preparing effective water-soluble sulfate detergents in which the sulfate portion is linked to a naphthenic residue through a methylol group.

Water-soluble synthetic detergents have generally consisted of either alkyl aryl sulfonates, alkyl sulfates, and non-ionic types of which a polyethylene oxide condensation product of an alkyl phenol is representative. These materials have failed to supply the ever-increasing demand for water-soluble detergent products.

This invention provides a method of preparing water-soluble detergents. The method comprises chlorinating a specific, relatively aliphatic and aromatic free naphthenic oil fraction; dehydrochlorinating the product; oxonating and reducing the resulting olefin from the previous step so as to obtain a naphthenic alcohol; sulfating the alcohol; and neutralizing the sulfated alcohol so as to obtain the water-soluble detergent product.

The product prepared by the process of this invention is distinct from all others hitherto made in that the sulfate portion of the detergent is linked to a naphthenic or alicyclic residue through a methylol group. The naphthenic residue can consist of completely hydrogenated cyclic hydrocarbons containing 5 or 6 carbons in the ring and may be alkylated with either straight chain or branched chain alkyl derivatives in one or more positions.

The nature of the naphthenic oil fraction utilized is extremely important. The process requires a relatively olefin, normal paraffin and aromatic free naphthenic fraction. These naphthene concentrate oils may be prepared by the well-known exhaustive sulfuric acid treatment of a petroleum distillate from selected sources followed by neutralization, washing and distillation or stripping to obtain the desired oil. The oil after this treatment contains no more than about 5 weight per cent normal paraffins. The boiling point of the oil utilized is in the range of from 200° C. to 320° C. with a molecular weight in the range of 175 to 225. Fractions below this range yield products of insufficient detergency, and above yield products of insufficient solubility. The naphthenes falling in this boiling point and molecular weight range are therefore rather complex in nature, and probably contain fused ring components, alkyl side chains, etc. These compounds would seem particularly adapted for

the production of the water-soluble detergents of this invention. The presence of more than a relatively small amount of olefins, normal paraffins and aromatics in the feed stock prior to chlorination results in the formation of undesirable polymeric materials, unstable chlorinated products and poor yields in the subsequent steps of dehydrochlorination and oxonation. Oils of Columbian or Coastal origin having high naphthenic content give extremely good results in the process of this invention.

In accordance with the process of this invention the specific oil fraction after treatment to remove olefins and aromatics is subjected to a chlorinating operation by passing gaseous chlorine into the liquid mixture while maintaining the temperature of the mixture substantially low, preferably below 100° C. The passage of chlorine into the naphthenic mixture is continued until the gain in weight of the hydrocarbon material indicates that the chlorination reaction has proceeded to the extent desired. A ratio of 0.5 mol (one atomic weight) of chlorine per mol of hydrocarbon has been found to effect a satisfactory chlorination of the hydrocarbon. Chlorination in excess of the indicated level results, on subsequent dehydrochlorination, in the production of undesirable dienes which polymerize to high boiling compounds.

When the increase in weight of the white oil indicates that chlorination has proceeded to the desired level, the entire body of the chlorinated material is subjected to dehydrochlorination to obtain a cycloolefinic product. This dehydrochlorination is conducted in liquid phase by conventional means, e. g., thermally, by aqueous alkali, by alcoholic KOH, by alkali in glycols, or catalytically through the use of catalysts, such as barium chloride or amines, such as quinoline and collidine, etc., depending upon manipulative advantages. When the dehydrochlorination is done by thermal means alone, the upper temperature limit is 320° C. The other means of dehydrochlorination utilize an upper temperature level of 300° C. and usually result in less undesirable color formation. The gaseous HCl is thus driven off in the case of thermal dehydrochlorination, leaving a liquid, predominantly monoolefinic, product. The chlorination-dehydrochlorination treatment results in the obtaining of a cyclic olefin which is especially suited for oxonation and the ultimate production of the indicated water-soluble detergents. If dienes are present as indicated by the bromine number, these dienes can be removed by reaction with maleic anhydride prior to sulfation.

The naphthenic olefin is then oxonated by the well-known Oxo process for the production of alcohols (see, e. g., U. S. Patent 2,327,066 and U. S. Bureau of Mines Publication R1 4270, "Critical Review of Chemistry of the Oxo Synthesis, etc." 1948). The term "Oxo" process is well understood in the art as referring to a process wherein an olefin feed is first reacted or "oxonated" with carbon monoxide and hydrogen at a temperature between 120° and 250° C., and under a pressure of about 150 to 400 atmospheres in the presence of a cobalt or similar catalyst, which may be introduced in the form of a fatty acid salt, to form aldehydes. As an illustration of a

particular naphthenic olefin the reaction proceeds as follows:

The aldehydes so formed are then catalytically hydrogenated to form the desired alcohols as follows:

The alcohol is then separated by conventional separation means known to the art.

The oxonation treatment is distinctly necessary so as to attach the CH_2OH radical onto the olefinic portion of the cyclic nucleus, i. e., to the naphthenic olefin, in order to subsequently form a naphthenic sulfate detergent.

The separated alcohol is then sulfated with "a sulfating agent" known in the art, such as concentrated sulfuric acid, oleum, sulfur trioxide, sulfur trioxide and liquid SO_2 , brom- and chlor-sulfonic acids in ethyl ether, etc., and their mixtures. Solvents may be used, such as ethyl ether, light hydrocarbons such as hexane, heptane, low-boiling petroleum ethers, or chlorinated solvents, etc. The sulfating agent may be added to the alcohol or vice-versa with the temperature kept in the range of -20° to 70° C. The amount of sulfating agent employed varies from 100 mol per cent based on the alcohol content of the feed, to an excess equivalent to roughly 1.5 times the weight of sodium sulfate per unit weight of sodium alcohol sulfate formed, on complete neutralization of the sulfation mixture. The sulfation results in the sulfate portion of the molecule being linked to the naphthenic residue through a methylol group.

The water-soluble sulfates are subsequently neutralized usually with caustic soda or soda ash and drum dried. Other neutralizing agents known in the art can also be employed. Unchanged hydrocarbons can be removed by extraction with solvents such as low-boiling naphtha, etc.

The following examples are given to illustrate this invention, and include both the processing of the naphthenic oils according to this invention and test results on the products as water-soluble detergents.

EXAMPLE I.—PREPARATION OF FEED STOCK

A Colombian gas oil having a boiling range of between 200° and 320° C. by Engler distillation and having in addition the following inspections:

Specific gravity	8633.
Kinematic viscosity at 100° F	2.99 centistokes.
Cloud point	-26° F.
ASTM pour	below -62.2° C.
Aniline point	56° C.
Neutralization number	4.32 mg. KOH/gm.

was treated in three portions with a total of 23% by volume of fuming sulfuric acid containing 25% dissolved SO_3 , the sludge formed at the end of each acid treat withdrawn and the sour oil equal to 78% of the original distillate neutralized with 20% sodium hydroxide, water washed to remove neutralization products, steamed with superheated steam for twenty minutes at a temperature of 115° C., and finally dried by percolation through 30-60 mesh Attapulgus clay. The acid treated oil showed the following inspections:

Color	+30 up Saybolt.
Open cup flash	110° C.
Wax cloud	-57° C.
Pour	below -62° C.
Kinematic viscosity at 100° F	3.11 centistokes.
Aniline point	78.5° C.
Neutralization number	Neutral.

The oil was then distilled under reduced pressure through a 15-plate fractionating column using a 2/1 reflux ratio and a 90% heart cut boiling between 5 and 95% of the charge was taken overhead between the temperature limits, extrapolated to atmospheric pressure, of 243 – 296° C. Molecular weight determinations showed this cut to con-

sist predominantly of a mixture of C_{14} – C_{15} naphthenic hydrocarbons. It was entirely free of unsaturates and contained less than a few per cent of normal paraffinic hydrocarbons and no aromatic hydrocarbons.

EXAMPLE II.—CHLORINATION OF FEED STOCK

1414 grams of the acid treated gas oil prepared in Example I was chlorinated under the influence of ultra-violet light with a fast stream of chlorine at a temperature between 45 – 50° C. over a period of 1 hour. After removal of dissolved hydrogen chloride and excess chlorine by blowing with a stream of dry nitrogen the oil was found to have gained 265 grams of chlorine. The crude chlorinated material was water washed to remove traces of HCl and then distilled under high vacuum. The major portion boiling between 95 to 150° C. at 0.35 mm. of Hg was analyzed for chlorine and found to contain 21.46 weight per cent chlorine.

EXAMPLE III.—DEHYDROCHLORINATION OF CHLORINATED FEED STOCK

893 grams of chlorinated feed stock was mixed with an excess of 2 Normal KOH in diethylene glycol and heated under reflux for two hours, at the end of which time the mixture showed separation into two layers. The hydrocarbon layer was separated, washed free of alkaline products and distilled under high vacuum. It boiled between 71 – 91° C. at 0.175 mm. Hg pressure and on analysis showed absence of any chlorine and had a bromine number equal to 59.4 centi-equivalents of bromine per gram.

EXAMPLE IV.—OXONATION OF OLEFIN FEED STOCK

357 grams of naphthenic olefin from Example III was dissolved in hexane and oxonated with a mixture of carbon monoxide and hydrogen with cobalt oleate as oxonation catalyst. At the completion of the oxonation run, the oxo aldehyde was reduced with nickel catalyst. Removal of the hexane gave 311 grams of crude product having a hydroxyl value of 0.143 centi-equivalents per gram. The crude product was accordingly esterified with excess of boric acid which gave 8 ml. of water of esterification. The borate ester was then topped under reduced pressure to a bath temperature of 280° C. and a vapor temperature of 130° C. The distillate which was hydrocarbon in nature was discarded and the remaining borate ester decomposed by refluxing with water for $1\frac{1}{2}$ hours. The purified alcohol which separated was water washed to remove acidic material and then distilled under high vacuum yielding 91.5 grams of a product boiling between 105 – 115° C. at a pressure of 0.075 mm. of Hg. The purified product showed a hydroxyl value equal to 0.4028 centi-equivalents per gram.

EXAMPLE V.—SULFATION OF NAPHTHENIC ALCOHOL

30.7 grams of the alcohol prepared in the preceding example were dissolved in 60 ml. of anhydrous ethyl ether and added dropwise at a temperature of 10 – 12° C. to 16.8 grams of chlorosulfonic acid which had been previously complexed with 35 ml. of anhydrous ethyl ether at a temperature of 0° C. After all of the alcohol had been added to the acid, the mixture was stirred for an additional half-hour at 10° C. and then poured into a mixture of 200 grams of ice and 30 ml. of 30% sodium hydroxide. The neutralized sulfate was then evaporated on a steam bath to remove ether and then sufficient 99% isopropyl alcohol added to bring the total volume to 480 ml. When cool, the solution of the sulfate in dilute alcohol was extracted three times with 200 ml. portions of petroleum ether so as to remove unsulfated product and then dehydrated with excess sodium carbonate. Evaporation of the petroleum ether extracts yielded 0.85 gram of unsulfated material. Analyses of the dehydrated alcohol solution indicated the presence of 42 grams of naphthenic alcohol sulfate equivalent to a theoretical yield

of 98%. A quantity of the alcoholic solution containing 37.7 grams was then taken, to which was then added 56.5 grams of sodium sulfate. The mixed solution containing 40% of active ingredient was then drum dried to a white-water-soluble flakey product.

EXAMPLE VI.—EVALUATION OF DETERGENT

Evaluation of the 40% active detergent prepared in Example V is shown in Table I below:

Table 1.—*Launderometer evaluation of naphthenic alcohol sulfate*

[Artificially soiled "Indian Head" muslin by Van Zile used in evaluation. Soiled cloth had average reflectivity of 21.8% compared to MgO.]

WASHED IN MEDIUM-HARD WATER CONTAINING 120 P. P. M. HARDNESS EQUIVALENT TO CaCO_3

	Reflectivity	Efficiency Compared to Commercial Sodium Lauryl Sulfate @ 0.5% = 100
Original Soiled Cloth	21.8	
Washed in Water (No detergent)	21.6	
Washed in Water + Detergent:		
0.1%	25.6	125
0.2%	25.9	135
0.375%	25.9	135
0.5%	26.0	138
Commercial Sodium Lauryl Sulfate @ 0.5%	24.8	100

WASHED IN HARD WATER CONTAINING 360 P. P. M. HARDNESS EQUIVALENT TO CaCO_3

	Reflectivity	Efficiency
Washed in Water (No detergent)	21.5	
Washed in Water + Detergent:		
0.1%	25.3	106
0.2%	25.9	122
0.375%	26.2	131
0.5%	25.9	122
Washed in Water + Commercial Sodium Lauryl Sulfate 0.5%	25.1	100

These results indicate that the detergents prepared by

the method of this invention were superior in both reflectivity and efficiency as compared with one of the best known and most favorably accepted commercial detergents.

5 Products from the process of this invention, as stated above, are unique in that the sulfate portion is linked neither to an alkyl nor an aromatic residue, but is attached directly to a naphthenic residue through a methyol group. The water-solubility and effective detergent action makes them extremely valuable.

It is to be understood that this invention is not limited to the specific examples, which have been offered merely as illustrations, since modifications may be made without departing from the spirit of this invention.

10 15 What is claimed is:

An improved process for preparing a naphthenic alcohol product suitable as an intermediate in the production of highly efficient water-soluble primary naphthenic alcohol sulfate detergents which comprises chlorinating a naphthenic hydrocarbon fraction which is substantially free of olefins, normal paraffins and aromatics, and which has a molecular weight in the range of about 175 to 225, and a boiling range of about 200° to 320° C., dehydrochlorinating the thus chlorinated naphthenic hydrocarbon fraction to produce an olefinic naphthenic product, thereafter subjecting said olefin product to a reaction with carbon monoxide and hydrogen in the presence of a cobalt catalyst at a temperature between about 120° to 250° C., and a pressure of about 150 to about 400 atmospheres to produce an aldehyde product having one more carbon atom than said olefinic material, thereafter hydrogenating said aldehyde product to produce a primary alcohol product, said primary alcohol product comprising a mixture of naphthenic alcohols.
